RAY E. HALL, OF PORTLAND, OREGON, ASSIGNOR OF ONE-HALF TO C. A. ROBERTSON,
OF PORTLAND, OREGON.

METHOD OF AND MEANS FOR TRANSLATING SOUNDS.

1,205,530.

Specification of Letters Patent. Patented Nov. 21, 1916.

Application filed April 16, 1914, Serial No. 832,219. Renewed April 20, 1916. Serial No. 92,532.

To all whom it may concern:

Be it known that I, RAY E. HALL, a citizen of the United States of America, residing at Portland, in the county of Multnomah, in the State of Oregon, have invented certain new and useful Methods of and Means for Translating Sounds, of which the following is a specification, reference being had to the accompanying drawings.

This invention relates to a method of and apparatus for translating sounds, particularly those produced in the receiving apparatus of wireless signaling devices, into mechanical movements to and fro, each corresponding in duration to the duration of the individual sounds produced.

Wireless signals are commonly detected and received by the use of a receiver worn by the operator adjacent the ear. The sounds produced by wireless receivers are generally so faint that the operator is subjected to a considerable nervous strain to detect all signals and messages and it has been found necessary in some instances to locate the receiver in a sound-proof room where absolute quiet is constantly maintained. Even with such precautions messages are sometimes unintelligible because of their faintness.

It is an object of my invention to provide a method of and apparatus whereby the sound waves set up by the diaphragm of a wireless receiver are automatically translated into mechanical movements to and fro, which may actuate suitable indicating devices to produce signals corresponding to these movements and of such magnitude that they are readily perceptible.

Other objects and advantages of my invention will be apparent as it is better understood by reference to the following specification when read in connection with the accompanying drawing, in which—

Figure 1 is a vertical section through a translating device, in which the sensitive jet is shown in disrupted form; Fig. 2 is an enlarged sectional view of a portion of the same apparatus, showing the jet directed through the opening in the vane, and Fig. 3 is a plan view of the vane.

Referring to the drawing, 1 indicates a nozzle, which is in operative communication with a source of fluid, either liquid or gaseous, under pressure and which is adapted

to direct a jet 1' of the fluid into the chamber 2, formed by the sound-proof casing 3, a hood 4 being provided at one end of the casing 3 to allow egress of the fluid while preventing injurious intrusion of sound and of air currents.

An extension of the casing 3 forms a chamber 5, communicating with the chamber 2, and a lever 6 is pivotally mounted at 7 on the bracket 7' near the junction of the two chambers. The end of the lever 6, extending into the chamber 2, is provided with a vane 8 of an area substantially equal to the cross-sectional area of the chamber 2. The vane 8 is provided with a central orifice 8' disposed, as indicated in Fig. 2, in the path of the fluid jet.

The opposite end of the lever 6 extends into the chamber 5 and is adapted to coöperate with a contact 9 to close the electrical circuit 10, containing a source of electrical energy 11, and an indicating device 12, which may be a relay or any other suitable form of signaling mechanism. A lever 6 is normally biased by a spring 6', disposed between an arm of the bracket 7' and the lever, to the position indicated in Fig. 2, in which the lever engages the contact 9.

A funnel is disposed through the casing 3 of the chamber 2, extending from a sound producing device, such as the wireless receiver 14, having a sound producing diaphragm 15 adapted to be actuated by variations of magnetic force of the magnet 16, when electrical impulses are received thereby, to a point adjacent the discharge orifice 17 of the nozzle 1.

The sensitive fluid jet is adapted to assume varying phases, involving relatively gross changes of form, when subjected to sound vibrations. Figs. 1 and 2 of the drawing represent two phases of the jet and it will be readily understood that the term "phases" as employed by me does not comprehend the minute variations in form, comprising the condensation and rarefactions which accompany the propagation of sound waves through the jet, since I do not utilize the jet to transfer sound waves *per se*.

The normal phase of the fluid jet, according to the usual operation of the device is indicated in Fig. 2, in which the jet is directed through the orifice 8', the lever 6 being biased by the spring 6' to engage the

contact 9 and close the electrical circuit 10. When sound waves, produced by the diaphragm 15 and directed by the funnel 13, impinge on the jet, it is disrupted, as indicated in Fig. 1, and since it can no longer pass through the orifice 8' the force of the jet is directed against the vane 8 and the lever 6 is turned about its pivot 7 against the action of the spring 6, breaking the circuit at contact 9. The disruption of the jet continues for a period equal in duration to the duration of the sound produced by the diaphragm 15 and assumes its normal phase as the sound ceases. The spring 6 immediately moves the lever 6 to again close the circuit at 9.

It is to be understood that the phases of the jet do not necessarily operate in the order described, since under certain conditions of pressure the jet may assume a normal phase, such as indicated in Fig. 1, and assume that indicated in Fig. 2 when sound waves impinge upon the jet. The operation of the vane in this case is identical with that previously described.

It will be readily understood from the foregoing description that I have devised a method and apparatus whereby the constant nervous strain under which wireless operators work is eliminated. In the preferred embodiment of the invention the indicating device 12 is a relay, which closes a local circuit to suitable indicating media. The indicating device 12 may, however, be utilized as a sounder, whereby the sounds produced by the diaphragm 15 are reproduced in an amplified form or may be simply a device to call the attention of the operator to the fact that a message is being received by the apparatus.

It will be obvious that various changes may be made in the form, construction and arrangement of the parts without departing from the spirit and scope of the invention or sacrificing any of its material advantages the form hereinbefore described being merely a preferred embodiment thereof.

I claim:

1. A method of causing sounds of relatively small volume to be readily perceptible, which consists in subjecting a vane capable of mechanical movement to and fro to the action of a fluid jet adapted to assume varying phases requiring relatively gross changes in form, impressing sound vibrations on said jet to produce said varying phases, whereby said vane is caused to move to and fro, said movements being of lesser period and greater magnitude than sound vibrations, and transferring the energy of said movements to suitable indicating media.

2. A method of causing sounds of relatively small volume to be readily perceptible, which consists in subjecting a vane capable of mechanical movement to and fro and

biased in one direction to the action of a gaseous jet adapted to assume varying phases requiring relatively gross changes of form, impressing sound vibrations on said jet to produce said varying phases, whereby said vane is caused to move to and fro, each of said movements corresponding in duration to the duration of the individual sounds, and transferring the energy of said movements to suitable indicating media. 75

3. A method of causing sounds of relatively small volume to be readily perceptible, which consists in producing a sensitive fluid jet adapted, when disrupted, to assume a varied form, causing sound vibrations to impinge on and disrupt said jet and subjecting a vane capable of oscillation to the action of said jet, whereby said vane is caused to oscillate, each of said oscillations corresponding in duration to the duration of the individual sounds and transferring the energy of said oscillations to suitable indicating media. 80

4. A method of causing sounds of relatively small volume to be readily perceptible, which consists in producing a sensitive gaseous jet adapted, when disrupted, to assume a varied form, causing sound vibrations to impinge on and disrupt said jet and subjecting a vane capable of oscillation to the action of said jet, whereby said vane is caused to oscillate, each of said oscillations corresponding in duration to the duration of the individual sounds, and transferring the energy of said oscillations to suitable indicating media. 85

5. A device for translating sound waves into mechanical movements of appreciably greater magnitude than sound vibrations, comprising oscillatable means, and means sensitive to sound adapted to assume varying phases and mechanically coöperating with said oscillatable means to cause oscillations of said oscillatable means, each oscillation corresponding in duration to the duration of the individual sounds and being of lesser period than sound vibrations. 105

6. A device for translating sound waves into mechanical movements of appreciably greater magnitude than sound vibrations, comprising pivoted means capable of oscillation, and means sensitive to sound adapted to assume varying phases and mechanically coöperating with said pivoted means to cause oscillations of said pivoted means, each oscillation corresponding in duration to the duration of the individual sounds and being of lesser period than sound vibrations. 115

7. A device for translating sound waves into mechanical movements of appreciably greater magnitude than sound vibrations, comprising pivoted means capable of oscillation, means sensitive to sound adapted to assume varying phases and mechanically coöperating with said pivoted means to cause 125

oscillations of said pivoted means, each oscillation corresponding in duration to the duration of the individual sounds and being of lesser period than sound vibrations, and indicating media controlled by the oscillations of said pivoted means.

5 8. A device for translating sound waves into mechanical movements of appreciably greater magnitude than sound vibrations, including means for producing a fluid jet adapted to assume varying phases when sound waves are impressed thereon, sound producing means disposed in proximity to said jet, and a pivoted member disposed in 10 the path of said jet and actuated thereby during one of its phases.

9. A device for translating sound waves into mechanical movements of appreciably greater magnitude than sound vibrations, including means for producing a gaseous jet adapted to assume varying phases when sound waves are impressed thereon, sound producing means disposed in proximity to said jet, and a pivoted member disposed in 15 the path of said jet and actuated thereby during one of its phases.

10. A device for translating sound waves into mechanical movements of appreciably greater magnitude than sound vibrations, including means for producing a fluid jet adapted to assume varying phases, when sound waves are impressed thereon, sound producing means disposed in proximity to said jet, a vane disposed in the path of said 20 jet and actuated thereby during one of its phases, and means for moving said vane in a direction opposite to the movement under the actuation of said jet, whereby to and fro movements of said vane are produced, each corresponding in duration to the duration of individual sounds.

11. A device for translating sound waves into mechanical movements of appreciably greater magnitude than sound vibrations, including means for producing a gaseous jet adapted to assume varying phases, when sound waves are impressed thereon, sound producing means disposed in proximity to said jet, a vane disposed in the path of said 25 jet and actuated thereby during one of its phases, and means for moving said vane in a direction opposite to the movement under the actuation of said jet, whereby to and fro movements of said vane are produced, each corresponding in duration to the duration of individual sounds.

12. A device for translating sound waves into mechanical movements of appreciably greater magnitude than sound vibrations, including means for producing a fluid jet adapted to assume varying phases when sound waves are impressed thereon, sound producing means disposed in proximity to said jet, and a vane biased in one direction 30 having an opening therein disposed in the

path of said jet, and adapted to be actuated thereby to move in the opposite direction during one of said phases, said jet passing through said opening during the other of said phases, whereby to and fro movements of said vane are produced, each corresponding in duration to the duration of individual sounds.

13. A device for translating sound waves into mechanical movements of appreciably greater magnitude than sound vibrations, including means for producing a gaseous jet adapted to assume varying phases when sound waves are impressed thereon, sound producing means disposed in proximity to said jet, and a vane biased in one direction having an opening therein disposed in the path of said jet, and adapted to be actuated thereby to move in the opposite direction during one of said phases, said jet passing through said opening during the other of said phases, whereby to and fro movements of said vane are produced, each corresponding in duration to the duration of individual sounds.

14. A device for translating sound waves into mechanical movements of appreciably greater magnitude than sound vibrations, including means for producing a fluid jet adapted to assume varying phases when sound waves are impressed thereon, sound producing means disposed in proximity to said jet, a pivoted vane having an opening therein disposed in the path of said jet and adapted to be actuated thereby during one of said phases, said jet passing through said opening during the other of said phases, and means for moving said vane in a direction opposite to the movement under the actuation of said jet, whereby to and fro movements of said vane are produced, each corresponding in duration to the duration of individual sounds.

15. A device for translating sound waves into mechanical movements of appreciably greater magnitude than sound vibrations, including means for producing a gaseous jet adapted to assume varying phases when sound waves are impressed thereon, sound producing means disposed in proximity to said jet, a pivoted vane having an opening therein disposed in the path of said jet and adapted to be actuated thereby during one of said phases, said jet passing through said opening during the other of said phases, and means for moving said vane in a direction opposite to the movement under the actuation of said jet, whereby to and fro movements of said vane are produced, each corresponding in duration to the duration of individual sounds.

16. A device for translating sounds into mechanical movements of appreciably greater magnitude than sound vibrations, including means for producing a fluid jet adapted to

assume varying phases when sound waves are impressed thereon, sound producing means disposed in proximity to said jet, a pivoted vane having an opening therein disposed in the path of said jet and adapted to be actuated thereby during one of said phases, said jet passing through said opening during the other of said phases, and a spring for moving said vane in a direction opposite to the movement under the actuation of said jet, whereby to and fro movements of said vane are produced, each corresponding in duration to the duration of individual sounds.

17. A device for translating sound waves into mechanical movements of appreciably greater magnitude than sound vibrations, including means for producing a gaseous jet adapted to assume varying phases when sound waves are impressed thereon, sound producing means disposed in proximity to said jet, a pivoted vane having an opening therein disposed in the path of said jet and adapted to be actuated thereby during one of said phases, said jet passing through said opening during the other of said phases, and a spring for moving said vane in a direction opposite to the movement under the actuation of said jet, whereby to and fro movements of said vane are produced, each corresponding in duration to the duration of individual sounds.

18. A device for translating sound waves into mechanical movements of appreciably greater magnitude than sound vibrations, including means for producing a fluid jet adapted to assume varying phases when sound waves are impressed thereon, a radiant energy receiver disposed in proximity to said jet, and a pivoted member disposed in the path of said jet and actuated thereby during one of its phases.

19. A device for translating sound waves into mechanical movements of appreciably greater magnitude than sound vibrations, including means for producing a gaseous jet adapted to assume varying phases when sound waves are impressed thereon, a radiant energy receiver disposed in proximity to said jet, and a pivoted member disposed in the path of said jet and actuated thereby during one of its phases.

20. A device for translating sound waves into mechanical movements of appreciably greater magnitude than sound vibrations, including means for producing a fluid jet adapted to assume varying phases, when sound waves are impressed thereon, a radiant energy receiver disposed in proximity to said jet, a vane disposed in the path of said jet and actuated thereby during one of its phases, and means for moving said vane in a direction opposite to the movement under the actuation of said jet, whereby to and fro movements of said vane are pro-

duced, each corresponding in duration to the duration of individual sounds.

21. A device for translating sound waves into mechanical movements of appreciably greater magnitude than sound vibrations, including means for producing a gaseous jet adapted to assume varying phases, when sound waves are impressed thereon, a radiant energy receiver disposed in proximity to said jet, a vane disposed in the path of said jet and actuated thereby during one of its phases, and means for moving said vane in a direction opposite to the movement under the actuation of said jet, whereby to and fro movements of said vane are produced, each corresponding in duration to the duration of individual sounds.

22. A device for translating sound waves into mechanical movements of appreciably greater magnitude than sound vibrations, including means for producing a fluid jet adapted to assume varying phases when sound waves are impressed thereon, a radiant energy receiver disposed in proximity to said jet, and a vane having an opening therein disposed in the path of said jet, and adapted to be actuated thereby during one of said phases, said jet passing through said opening during the other of said phases, whereby to and fro movements of said vane are produced, each corresponding in duration to the duration of individual sounds.

23. A device for translating sound waves into mechanical movements of appreciably greater magnitude than sound vibrations, including means for producing a gaseous jet adapted to assume varying phases when sound waves are impressed thereon, a radiant energy receiver disposed in proximity to said jet, and a vane having an opening therein disposed in the path of said jet, and adapted to be actuated thereby during one of said phases, said jet passing through said opening during the other of said phases, whereby to and fro movements of said vane are produced, each corresponding in duration to the duration of individual sounds.

24. A device for translating sound waves into mechanical movements of appreciably greater magnitude than sound vibrations, including means for producing a fluid jet adapted to assume varying phases when sound waves are impressed thereon, a radiant energy receiver disposed in proximity to said jet, a pivoted vane having an opening therein disposed in the path of said jet and adapted to be actuated thereby during one of said phases, said jet passing through said opening during the other of said phases, and means for moving said vane in a direction opposite to the movement under the actuation of said jet, whereby to and fro movements of said vane are produced, each corresponding in duration to the duration of individual sounds.

25. A device for translating sound waves into mechanical movements of appreciably greater magnitude than sound vibrations, including means for producing a gaseous jet 5 adapted to assume varying phases when sound waves are impressed thereon, a radiant energy receiver disposed in proximity to said jet, a pivoted vane having an opening therein disposed in the path of said jet 10 and adapted to be actuated thereby during one of said phases, said jet passing through said opening during the other of said phases, and means for moving said vane in a direction opposite to the movement under the actuation of said jet, whereby to and fro movements of said vane are produced, each corresponding in duration to the duration of individual sounds.
26. A device for translating sounds into mechanical movements of appreciably greater magnitude than sound vibrations, including means for producing a fluid jet adapted to assume varying phases when sound waves are impressed thereon, a radiant energy receiver disposed in proximity to said jet, a pivoted vane having an opening therein disposed in the path of said jet and adapted to be actuated thereby during one of said phases, said jet passing through said opening during the other of said phases, and a spring for moving said vane in a direction opposite to the movement under the actuation of said jet, whereby to and fro movements of said vane are produced, each corresponding in duration to the duration of individual sounds.
27. In a device of the character described, the combination of a sound proof casing, oscillatable means pivotally mounted within said casing, and means sensitive to sound adapted to assume varying phases and mechanically coöperating with said oscillatable means to cause oscillations of said oscillatable means, each oscillation corresponding in duration to the duration of individual sounds and being of lesser period than sound vibrations.
28. In a device of the character described, the combination of a sound proof casing 50 oscillatable means pivotally mounted within said casing, means sensitive to sound adapted to assume varying phases and mechanically coöperating with said oscillatable means to cause oscillations of said oscillatable means, each oscillation corresponding in duration to the duration of individual sounds and being of lesser period than sound vibrations.
29. In a device of the character described, the combination of pivoted means capable of oscillation, and means for causing oscillation of said pivoted means comprising a sensitive fluid jet adapted to assume varying phases involving relatively gross changes of 55 form and mechanically coöperating with said pivoted means.
30. In a device of the character described, the combination of a sound proof casing, means within said casing for producing a fluid jet adapted to assume varying phases when sound waves are impressed thereon, sound producing means disposed in proximity to said jet, a pivoted member within said casing, normally biased in one direction, 70 a vane having an opening therein at one end of said member, in the path of said jet and adapted to be actuated thereby during one of said phases, whereby movements of said member are produced, each corresponding 75 in duration to the duration of individual sounds, and indicating media controlled by said movements.
31. In a device of the character described, the combination of a sound proof casing, 80 means within said casing for producing a gaseous jet adapted to assume varying phases when sound waves are impressed thereon, a radiant energy receiver disposed in proximity to said jet, a pivoted member 85 within said casing, normally biased in one direction, a vane having an opening therein at one end of said member, in the path of said jet and adapted to be actuated thereby during one of said phases, whereby movements of said member are produced, each corresponding 90 in duration to the duration of individual sounds, and indicating media controlled by said movements.
